UNITED STATES PATENT OFFICE.

LOUIS E. VALCOURT, OF PAWTUCKET, RHODE ISLAND, ASSIGNOR TO LOUIS STERN CO.,
OF PROVIDENCE, RHODE ISLAND, A CORPORATION OF RHODE ISLAND.

BRACELET HOOK.

Application filed May 12, 1925. Serial No. 29,729.

This invention relates to an improved construction of so-called watch bracelet hook, and has for its object to provide such a hook which is more particularly adapted to be used in connecting a bracelet to a wrist watch; and the object of this invention is to provide such a hook in which the jaw member is pivoted in the body of the hook and is provided with an operating arm extending through the front wall of the hook by the manipulation of which arm the pivoted jaw member may be swung outwardly from the fixed jaw member in connecting and disconnecting the hook to and from the bail of the watch.

A further object of this invention is to form the outer jaw member of the hook nearly straight to readily enter the bail member of the watch and the lower or swinging jaw member of the hook in hook shape to close against the fixed jaw member to facilitate the connecting of the hook to a watch having a depending bail member beneath the overhanging portion thereof.

With these and other objects in view, the invention consists of certain novel features of construction, as will be more fully described, and particularly pointed out in the appended claims.

In the accompanying drawings:

Figure 1 is an edge view showing a portion of a watch with my improved type of hook connected to the bail formed on the under side of the overhanging portion thereof.

Figure 2 is a face view of the body portion of the hook in unfolded position as struck from sheet stock.

Figure 3 shows the wings or side portions of the hook-body as folded.

Figure 4 shows the notched wing portions of the body as partially closed upon the pivot pin of the jaw member.

Figure 5 is a perspective view showing the inner face of the jaw member.

Figure 6 shows the jaw member as mounted in the body of the hook both being partially in section through the pivot pin connecting the two.

Figure 7 is a longitudinal central sectional view through the body member and showing the same as connected to the bail of a watch, shown in dotted lines.

Figure 8 is a perspective view of my improved bracelet hook.

It is found in the construction of wrist watches, of advantage to provide extending ornamental portions on their ends and to also provide rearwardly-extending bail members on the under side of these ornamental extending portions, and therefore in order to be able to connect a bracelet hook to these bail members which lie close to the under surface of the overhanging portions, it is necessary that the top wall or plate 55 of the hook-shaped member be provided with a shank portion and an end portion which is adapted to extend through this bail 60 on the watch and to pivot the jaw member 65 in the body of the hook with an upwardly- 70 extending end portion to close against the under side of the straight jaw portion to engage the watch bail; also it is found of advantage to provide an operating arm extending through the front plate of the hook 75 into position to be engaged when the jaw is to be opened to receive or permit the removal from the bail of the watch; and the following is a detailed description of the 80 present embodiment of my invention and showing one means by which these advantageous results may be accomplished:—

With reference to the drawings, 10 designates the body of my improved form of bracelet hook which is preferably formed of 85 sheet stock, the same having a top wall or plate 11 with a forwardly-extending shank or outer jaw portion 12 formed to readily engage or be passed through the bail member 13 of a wrist watch 14. The body portion 90 of this hook member is provided with rearwardly-extending edge walls 15 and inwardly foldable members 16, also this body portion is provided with wing portions 17 which are notched at their edges 18 and 95 adapted to be folded inwardly into position as illustrated in Figures 3 and 6, over the pivot pin 19 on which the swinging jaw 20 is mounted.

This swinging jaw is provided with a 100 pair of pivot ears 21 having eyes 22 through which the pivot pin 19 passes and a coiled spring 23 has its opposite ends arranged to act between the front plate of the hook and the rear plate of the swinging jaw to move 105 this jaw member outwardly on its pivot to

carry its hook-shaped end 24 up against the straight end portion 12 of the body of the hook.

At the rear of this swinging jaw, I have formed an operating arm 25 which extends across the opening between the front and back plates of the body member and through the opening 26 of the front plate, its end portion 27 being in position to be readily engaged by the thumbnail of the operator and by drawing the same upward and pressing it forward towards the engaging end of the hook member the under jaw 20 is caused to swing on its pivot outwardly and away from the fixed jaw 12 to receive the bail 13 of the watch or to release the same when the bracelet is to be released from the watch.

By my improved construction, it will be seen that this hook may be readily attached to a bail that lies close against the under side of the overhanging portion of the watch, and may also be swung from the front jaw of the hook by a simple swinging movement of the operating member thus obviating the necessity and inconvenience of passing the finger around beneath the hook in order to open it which is found in practice to be quite a difficult and inconvenient operation.

My improved hook is very simple and practical in construction and durable and by its use the ends of a watch bracelet may be connected to and disconnected from the bail of a wrist watch even though the bail be close against the overhanging portions of the watch.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A watch bracelet hook formed of sheet stock and having a pair of cooperating jaw members pivotally connected together to swing outwardly from each other, and an operating arm on one of said members extending through the front portion of the other of said members.

2. A watch bracelet hook having a body portion formed of sheet stock and having an extended fixed jaw member, a jaw member pivoted to said body portion to open outwardly from said fixed jaw member, and an operating arm on said pivoted jaw extending through the front walls of said body.

3. A watch bracelet hook comprising a body portion having an extending top plate in substantially a single plane and of a size to readily extend through the bail of a wrist watch, a jaw member pivoted in said

body portion to swing outwardly from engagement with said top plate and having an operating arm extending through said top plate to be manually operated from the top thereof.

4. A watch bracelet hook comprising a body portion having a plate member extending therefrom, of a size to pass through the bail of a wrist watch, a jaw member having an operating arm on one end thereof of extending through the top wall of said body, and a hook-shaped end to engage said plate member, said jaw being pivoted in said body intermediate its ends whereby a movement of said arm outwardly from the top wall and toward its hook end moves said jaw and plate members apart to receive the watch bail.

5. A watch bracelet hook comprising a body portion with an opening in its top wall and having its top wall extended in substantially the plane thereof to form the shank member of the hook for passing through the bail of a wrist watch, a jaw member pivoted on said body portion and having a hook-shaped end to swing to and from engagement with said shank member, a spring for normally holding said members in closed contacting position, and an operating arm extending through said opening in the top plate to be manually engaged for moving said members to open position.

6. In a watch bracelet hook, a body portion having inwardly-folded wings with notches in their inner portions, a jaw member having inwardly-folded ears, a pivot pin extending through said ears and engaging the notches in said wings to pivot said jaw member relative to said body.

7. A watch bracelet hook comprising a body portion having top, side and bottom walls folded from sheet stock, the top wall having an extending plate lying substantially in a single plane, a jaw member having a hook-shaped end and inwardly folded ears, a pivot pin extending through said ears, a spring coiled about said pin having portions engaging said jaw and body portion, inwardly-turned wings on said body having notches to engage the ends of said pin and hold it in said body, an operating finger on said jaw extending through the top wall of said body for manual operation of said jaw from the front thereof to move said jaw on the axis of said pin to and from engagement with the edge of said extending plate.

8. A watch bracelet hook formed of sheet stock and having a pair of cooperating jaw members pivotally connected together to swing outwardly from each other and of substantially the same length from the pivotal connection, one of said members being in substantially a single plane and the other of said members being hook-shaped at its

end and substantially meeting the end of the first said member.

9. A watch bracelet hook comprising a body portion having an extending top plate in substantially a single plane and of a size to readily extend through the bail of a wrist watch, a jaw member pivoted in said body portion to swing outwardly from

engagement with said top plate and an extension manually operable from the top of the hook for separating said jaw member and plate.

In testimony whereof I affix my signature.

LOUIS E. VALCOURT.
